(No Model.)

H. ANDREWS.
MINIATURE AMMUNITION.

No. 552,090.

Patented Dec. 31, 1895.

UNITED STATES PATENT OFFICE.

HARRY ANDREWS, OF LONDON, ENGLAND.

MINIATURE AMMUNITION.

SPECIFICATION forming part of Letters Patent No. 552,090, dated December 31, 1895.

Application filed December 31, 1892. Renewed October 14, 1895. Serial No. 566,671. (No model.) Patented in England May 13, 1889, No. 7,927; in Belgium December 11, 1889, No. 88,841; in France December 13, 1889, No. 202,572; in Austria-Hungary January 3, 1890, No. 1,087; in Spain March 8, 1890, No. 10,327, and in Italy January 13, 1893, No. 33,251.

To all whom it may concern:

Be it known that I, HARRY ANDREWS, a subject of the Queen of Great Britain, residing at Woolwich, London, in the county of Kent, England, have invented a new and useful Improvement in Projectiles for Firearms, (for which I have obtained patents in Great Britain, No. 7,927, bearing date May 13, 1889; in France, No. 202,572, bearing date December 13, 1889; in Belgium, No. 88,841, bearing date December 11, 1889; in Italy, No. 33,251, bearing date January 13, 1893; in Spain, No. 10,327, bearing date March 8, 1890, and in Austria-Hungary, No. 1,087, bearing date 15 January 3, 1890,) of which the following is a specification.

The object of my invention is to facilitate the use of miniature ammunition with magazine-rifles, machine-guns and other firearms. Heretofore an apparatus for adapting firearms for use with miniature ammunition comprised a tubular piece or block adapted to hold the miniature cartridge in its forward end and having at its rear end a head or flange corresponding in form and dimensions to that of the ordinary service-cartridge, a sliding pin being arranged within and extending through the said tubular piece or block to communicate to the primer of the miniature cartridge the blow or impact of the firing-pin, hammer or striker of the firearm. The miniature cartridges for use with this apparatus require to be specially formed at the rear end or base to permit their attachment to the said tubular piece or block. By my invention I provide an apparatus of this kind or class which is simpler in construction but more efficient than that described above. Moreover, by reason of the improved construction of my apparatus miniature cartridges with ordinary rim bases, heads or flanges can be firmly secured therein. The said apparatus is, therefore, well adapted for use in magazine or repeating firearms.

An important feature of my said invention is the adaptation of an ordinary or service cartridge case or shell for containing a tubular piece or block. The base of this cartridge case or shell is bored out so that the minia-

ture cartridge and the block or plug containing the communicating pin or striker can be inserted therein from the rear end thereof. Therefore the entire apparatus with the miniature cartridge therein resembles an ordinary or service cartridge, and can be as readily fed from the hopper or magazine into the chamber of a gun.

My said invention, moreover, comprises other improvements hereinafter set forth.

In the accompanying drawings I have shown how my said invention may be conveniently and advantageously carried into practice, of which—

Figure 1 is a longitudinal central section of one form of my improved apparatus, the miniature cartridge being shown in side elevation. Fig. 2 is a rear elevation of the said apparatus. Fig. 3 is a side elevation illustrating details of construction. Fig. 4 is a side elevation illustrating a slight modification of the said apparatus. Fig. 5 is a longitudinal central section showing another form or modification of my said apparatus. Fig. 6 shows a further modification of construction.

Similar letters refer to corresponding parts throughout the several views.

A is an ordinary or service cartridge case or shell, which may with advantage be made of steel.

B is the miniature cartridge. The base of the said cartridge case or shell A is, as above stated, bored out to permit the insertion of the miniature cartridge B from the rear end of the said shell.

The shell of the miniature cartridge is made of such diameter that the forward part thereof will pass through the reduced portion or neck of the shell A and its rear portion will fit tightly therein, the rim B' of the miniature cartridge abutting against the internal shoulder of the shell A, as shown in Fig. 1, so that the cartridge is retained firmly in position in the said shell.

C is the tubular block or plug, which is inserted into the body of the shell A and fits the same closely at each end, and which is formed of wood, metal or other suitable material or of wood strengthened with metal where

necessary. In the central hole C' of the block or plug C is fitted to slide longitudinally the communicating pin or striker D.

In the apparatus shown in Figs. 1 to 3 the said communicating pin or striker D is retained in the said block or plug C by means of a set-screw E, the inner extremity of which enters a circumferential groove D' in the pin D. This groove is so made as to permit the necessary longitudinal or endwise play or movement of the said pin in the block or plug C.

F is a head secured upon the rear extremity of the communicating pin or striker D by means of screw-threads; or it may be secured thereon in any other suitable manner that will permit its ready removal from the said pin or striker when desired; or the said head may be separate from the pin or striker and so held in the block or plug C that it can move longitudinally therein and will bear against the rear end of the said pin or striker. The removable head F receives the impact of the striker, hammer or firing-pin of the gun, and when worn out or damaged by repeated blows therefrom may be readily removed and replaced by a new one, thus obviating the necessity for replacing the entire pin or striker. It is obvious, however, that I can if desired form the head solidly upon the pin or striker.

30 A recess or cavity C² is formed in the block or plug C to receive the said head F and permit the necessary movement thereof when struck by the striker, hammer or firing-pin of the gun.

35 G is a split ring which is arranged in a circumferential groove C³ in the block or plug C, and which, when the said block or plug is inserted into the shell A, will be slightly compressed and will retain the said block or plug

40 in position in the said shell, while permitting its withdrawal therefrom when desired. The block or plug C may be formed as shown for the sake of likeness, or it may be of any other suitable shape.

45 The removal of the block or plug C and of the shell of the miniature cartridge B from the shell A after the said miniature cartridge has been fired and the apparatus extracted from the firearm can be readily effected. For this

50 purpose the said shell of the miniature cartridge is pushed inward or backward, together with the block or plug C, sufficiently to enable the latter to be withdrawn from the rear end of the shell A. The said miniature shell may 55 then be easily removed and another miniature cartridge inserted in its place. The block or plug being reinserted in the shell A, the apparatus is again ready for use.

I sometimes form one or more slits in the forward end or neck of the shell A, as at A², Fig. 4, to facilitate the insertion of the miniature cartridges therein, and more particularly the withdrawal of the expanded empty shells therefrom.

65 For quick-firing and other guns of larger caliber I prefer to construct my apparatus as

shown in Fig. 5. In this modification of my invention the head F is formed with a flange or collar F', and the pin or striker D is retained in the block or plug C by means of a sleeve H, which is screwed into the recess or cavity C² in the said plug and is provided with an internal flange H', serving as a stop or abutment for the collar F' of the head F. As this stop or abutment retains the pin or striker D in the block or plug C, I am enabled to dispense with the set-screw E, above mentioned. The said sleeve H can be readily withdrawn to permit the removal and replacing of the head F. By this arrangement the manufacture of the block or plug C is simplified, as the said plug can be cast with a suitable core, and it will then only be necessary to bore the same out at each end and form the screw-threads in the cavity C².

It will be seen that by reason of the construction of my apparatus in the manner above described I am enabled to dispense with a spring for effecting the backward or return movement of the pin or striker D after it has been driven forward to fire the miniature cartridge. The backward or return movement of the said pin or striker in my apparatus can be effected by hand after the removal of the block or plug from the shell A, or it will be effected in the operation of reinserting the said block or plug in the said shell behind the miniature cartridge. My apparatus is, therefore, more advantageous, inasmuch as when a spring is employed for this purpose a certain amount of energy is required to compress the said spring. Consequently the blow struck by the striker, hammer or firing-pin of the gun is not as effective as it is without the spring, and misfires are liable to result.

It is obvious, however, that in cases where the force of the blow or impact of the striker, hammer or firing-pin of the gun is greater than is required to fire the miniature cartridge I can introduce a spiral or other spring, in combination with the pin or striker D, to partially counteract this force and thus diminish the force of the blow communicated through the said pin or striker D to the primer of the miniature cartridge.

Instead of the split ring hereinbefore described I can employ any other suitable spring or springs for retaining the block or plug C in the shell A. For instance, I sometimes form a spring by making one or more slits A², Fig. 6, in rear end or body of the cartridge-shell A, and contracting the said shell at this end, as shown; or I can employ other suitable means for holding the aforesaid block or plug firmly in position in the body of the shell A, while permitting its withdrawal therefrom when desired. It is obvious, moreover, that I can somewhat further modify the construction of my improved apparatus without departing from the nature of my said invention. For instance, instead of an ordinary or service cartridge-shell bored

out at its rear end, I can, if desired, employ a steel or other tube so formed as to accurately fit the chamber of the firearm.

My improved apparatus can be more easily and cheaply manufactured than those heretofore used. Moreover, the apparatus may be so constructed that, together with the miniature cartridge, it will be of the same weight and externally of the same form as the ordinary service-cartridge, thus permitting or facilitating the feeding of the said apparatus from the hopper or magazine into the chamber of a gun.

Having now particularly described and ascertained the nature of my said invention and in what manner the same is to be performed, what I desire to claim is—

1. A tubular piece, adapted to hold a cartridge composed of a shell A, provided with an internal tubular block C, carrying the communicating pin or striker D, and having

a split ring G, surrounding said block C, at its front end, substantially as and for the purpose set forth.

2. A tubular piece adapted to hold a cartridge composed of the shell A, made of metal of the shape shown; the miniature cartridge B, with rim B', inserted in shell A; the tubular block C, placed in the shell and holding the communicating pin or striker D; the head F, placed in cavity C², of the block C, as described; and the split ring G, surrounding the block C, at the front end, as described, and all arranged as described and for the purpose set forth.

In testimony that I claim the foregoing I have hereunto set my hand this 30th day of January, 1892.

HARRY ANDREWS.
